UNITED STATES PATENT OFFICE

2,452,076

GUN MOUNT

Myron C. Spencer, Ocean Grove, N. J.

Application February 7, 1944, Serial No. 521,376

2 Claims. (Cl. 89—37)

(Granted under the act of March 3, 1883, as amended April 30, 1928; 370 O. G. 757)

1

The invention described herein may be manufactured and used by or for the Government for governmental purposes without the payment to me of any royalty thereon.

This invention relates to quick-action traverse and elevation changing gun mounts and mounts of similar action for other purposes.

The invention has for an object to present a construction in which a single gunner may operate the gun quickly both for traverse and elevation and at the same time fire the gun when of an automatic loading type, with a high degree of accuracy, as compared to conventional mounts.

It is an important object to relieve the gunner from the expenditure of much effort and energy now involved by the conventional mount for a hand-pointed gun, wherein the gunner walks around the gun as it is swung, in traverse, and at the same time it is sought to give the gunner a more steady orientation in relation to the gun without the need for shoulder rests, stocks and the like.

A further purpose is to enable the gunner to more effectively concentrate mentally on the movement of the target and the factors entering into the aiming of the piece, notwithstanding that quicker movements of the gun in traverse and elevation are possible, which are further objects of the invention.

Another object is to present a mount in which some basic desirable features of conventional mounts may be embodied, yet eliminating the need for many others, so that the mount may be simple to produce, at the same time that improvements herein enumerated are attained. Thus it is sought to eliminate the need for the heavy 3-position trigger frame mechanism and grip structure and enable the use of a simple pistol grip and trigger immediately at the gun. Also the sight may be greatly lightened and located close to the axis of the gun, reducing errors in calculating or estimating parallax angles, which is specially important in close range anti-aircraft fire.

It is an important aim to attain the last named improvement without requiring excessive height in the mount.

A further important aim of the invention is to enable the gunner to sight the weapon without stooping, ducking or cocking his head at any awkward angles.

A still further attainment in view is to enable greater use of space near the gun for other purposes, such as accommodation of men or material in trucks or confined situations, and on ship-

board to enable the placing of a gun near stores or gear when not heretofore possible.

One important use which it is sought to attain is the possibility of mounting a machine gun so that it may be moved with its mount instantly from an out-of-the-way situation to an attack or firing position, as, for instance on a swinging bracket, which in fighting position may extend laterally from a truck body, or the side of a vessel or barge.

In the attainment of these and other objects and advantages, as a part of the embodiment of the invention, I have utilized a gear drive for traverse, operated by pedal cranks in this instance, and it is a very important object of the invention to enable an independent free manual swinging of the gun for traverse, and so make the pointing of the gun independent of the gear connections within proper limits yet retaining the advantage and benefit of the quick rotation of the gun assembly and gunner on the mount by pedal action. In this way uncertainty of azimuth adjustment due to lost motion or back lash in gears is obviated.

Additional objects, advantages and features of invention reside in the construction, arrangement and combination of parts involved in the embodiment of the invention as will appear from the following description and accompanying drawings, wherein:

Fig. 1 is a side elevation of a mount, the pedestal shown partly in section, constructed in accordance with my invention, a gun and sight being formally shown, though not in complete detail or proportions and particularly as to the gun, since gun forms adapted or adaptable to use on my mount are known, and the gun comprises no novel part of my invention.

Fig. 2 is a rear elevation of Fig. 1 with upper portion of the extensible sleeve shown partly in section.

Fig. 3 is a cross section on the line 3—3 of Fig. 1. Fig. 4 is a cross section on the line 4—4 of Fig. 1.

Fig. 5 is a cross section on the line 5—5 of Fig. 1.

Fig. 6 is a cross section taken generally on the line 6—6 of Fig. 1, the pedal being shown in its lowermost position.

Fig. 7 is an enlarged side elevation partly in section.

Fig. 8 is a similar view of a modification.

Fig. 9 is a schematic detail of a valve for the modification, in raising position.

Fig. 10 is a schematic detail of a valve for the modification, in lowering position.

Fig. 11 is a schematic detail of a valve for the modification, in stopping position.

Fig. 12 is a detail elevation of the crane arm mounting.

Fig. 13 is a fragmentary top view of the last named, illustrating the operation of the locking flange.

Fig. 14 is a rear elevation of a truck on which my invention is incorporated.

Fig. 15 is a side elevation of a cradle mount element, the base of the mount omitted. The seat, not shown, would be attached to the left hand side of the standard 102 as shown in this view.

Fig. 16 is a rear elevation of Fig. 15.

Fig. 17 is a section on the line 17—17 of Fig. 15.

Fig. 18 is a detail of a modification of the pedal drive.

Fig. 19 is an enlarged section of the base of the hydraulic mount.

Referring to the drawings by characters of reference, there is illustrated a mount comprising a pedestal or foot mounting 15, consisting of a base plate 14 which may be the same size as that of a well known prior pedestal mount, fixed or integrally formed on which there is an upper standing body 16 horizontally flanged at its upper part to permit attachment thereto of a bevelled ring gear 17. A simple step bearing recess is formed in this body, concentric with the gear, and stepped therein is a vertical shaft 18 of substantial dimensions for the uses contemplated.

Base traverse.—Diametrically arranged radial stud shafts or pins 19 are fixed at opposite sides of the shaft 18, on which there are revoluble respective small bevel gears 20 meshed with the gear 17, and keyed to which are pedal crank arms 21, having conventional pedals 22 similar to those used on bicycles. Conventional crank construction such as used in bicycles with gear drive may be substituted if desired. The gears 20 are so meshed with the ring gear as to position the cranks on opposite radii of the axis of the small gears, and the cranks will be so maintained thereafter throughout the operation of the device.

Seat.—At a suitable distance above the gears a seat bracket arm 23 is mounted on the shaft 18, consisting of flat, steel piece longitudinally slotted at its base and held to the shaft adjustably as to height by means of thumb screws 24 or other fastening. The arm extends diagonally upward and outward from the shaft and carries at its upper end a conventional form of seat 25 suitable for the uses indicated.

Accommodation of line of sight and eye level.—Slidable on the shaft, there is an extensible sleeve 26, and mounted thereon is an elevator pinion 27 meshed with a rack 28, formed on the shaft 18 in line with the seat bracket, the pinion being operated by a hand wheel 29 and crank handle 30, by which the sleeve may be raised and lowered on the shaft 18.

Free pointing action.—Means are provided on the upper end of the sleeve 26 for mounting a gun, where there is swivelled a pivot yoke 31, having upstanding parallel ears 32 between which there is fitted a rocker head 32, supported by an elevating pivot pin 33 engaged through the ears and head 32. The rocker head is connected by a neck or radial extension 34 to the frame 35, cradle, or other part of the gun or parts to be assembled therewith. The swivel 31 includes an upper head part 36 of the same external diameter as the sleeve 26, and is relieved at its lower part so as to form a shoulder 37 which in this instance rests directly on the upper end

of the sleeve 26 to revolvably support the swivel, the relieved part of the swivel may be termed a stem 38 which fits snugly and revolvably in the sleeve, extending downwardly in the sleeve a substantial distance to maintain a stable axial relation to the sleeve and shaft. At an intermediate part of the stem 38 a flat bottomed circumferential groove 39 is formed on the stem 38, and engaged through the wall of the sleeve there is a retainer screw 40 or more, projecting into the groove so as to hold the shank revolvably in the sleeve.

At the upper end of the sleeve a broad shallow slot 41 is formed, open on the end of the sleeve and on the swivel yoke 31 a lug 42 is formed as a continuation of the peripheral material of the head 36 extending below the shoulder 37. The lug is narrow enough to permit its movement from side to side in the slot under corresponding rotary movements of the yoke 31 on the axis of the tube, and thereby such rotation is limited by engagement of the lug against either side of the slot. This will correspondingly limit traverse of the gun when the shaft 18 is stationary. The shaft 18 may be retained in its bearing in the foot piece 15 by any suitable means, a C-spring 43 being shown in the present instance, contracted into a groove 44 formed on the outer periphery of the shaft at a level with the under side of the ring gear, the spring being of such transverse measurement as to engage under and be held against upward movement by the gear. The inner bearing surface of the foot piece is relieved or rabbeted at its upper part to accommodate the C-spring. The relative movement of the swivel on the sleeve 26 may be from fifteen to thirty degrees or more and if desired a yielding means may be incorporated to yieldingly oppose movement of the lug 42 when nearing either end of the slot 41.

Foundation support.—In one use of the invention as a gun mount or searchlight control, the base plate 14 is mounted on the outer end of a crane arm 45, which may have a plate 46 of a size the same as the plate 14, to which the latter is bolted or clamped, clamping devices being now in use suitable for such purpose in gun mounts.

The arm 45 is formed with horizontal upper and lower ears 47 and 48 held by a king pin 49 which is revolvable in a knuckle 50, formed on a substantial bracket plate 51 adapted to be bolted to side plates or frame of a truck 45', tank or other structure. The knuckle is formed with a semi-circular bearing flange 52 based on the plate 51, and having peripheral notches 53 therein a each side near the plate, and a central notch 54 on a radius normal to the plane of the plate. On the inner and under side of the ear 47 there is pivoted an L-shaped dog or latch lever 55 having a short latch arm 56 adapted to enter any one of the notches 53—54 when aligned therewith and a normally pendent long operating arm 57 the extremity of which lies near but stops short of the lower ear 48 of the crane. The lever 55 is thus operable to hold the crane extended when the lever engages the central notch 54 or hold it retracted close beside a supporting structure to which the bracket 51 may be attached.

Any usual expedients used in prior mounts and applicable here may be added as discretion dictates. Due to the fact that many such are known in readily applicable form, I have not disclosed clamps for limiting traverse, vibration and recoil cushioning means in the mount, ball bearings and other anti friction bearings applicable in the step

bearing, the swivel and otherwise; mounting of ammunition case on the gun, toe clips on the pedals, and means to limit depression of the gun too far when among own troops or to limit traverse where necessary. The formal representation of a gun 60 which is made in the drawings is not intended to represent any perfected gun known, but includes a schematic indication of an air cooled barrel 58, a framing structure 35 and pistol grip and trigger at 61.

In the use of the mount as described, it may have the foot plate 14 bolted to a deck, or to an adapter plate of greater radius to afford a stable base to be bolted to a wood deck or for other reasons, such added base elements being well known. Also a well known form of tripod leg assembly may be provided on the foot piece 15, these being well known and therefore not illustrated.

Operation.—In operation, assuming the mount built substantially in the specific form illustrated in Figs. 1 to 9, the gun mounted on the swinging crane arm 45 is positioned close beside the body of the truck 45', and the gunner may be either in the seat 25, or in the body of the truck, or elsewhere. In case the truck is one with bows on which a covering material is disposed, the gun and mount are preferably positioned with the muzzle of the gun and the seat in a vertical plane parallel to the side of the body, the gun having its muzzle either forwardly or rearwardly with respect to the truck. It will be so held by engagement of the latch 55 in the respective notch 53. For action, the latch 55 is disengaged by swinging the arm 57 outward to clear the arm 56 from the notch and the crane arm swung outward to position at right angles to the side of the truck, the latch 55 then engaging in the notch 54 either by action of gravity on the long arm 57 or by manual or spring pressure on the latter. When the arm is swung outward and latched in place, the gunner may now take position in the seat 25, with his feet on respective pedals, grasping the grip 61 in one hand and the elevator wheel or crank 29—30. The target being in view or otherwise located, the gunner operates the pedals to drive the planetary gears 20 on the large gear 17 until the shaft 18 is turned so as to present the gun in an azimuth plane approximating the position of the target, and by the grip 61 gives the gun an elevation approximating that which will produce a trajectory of proper range. Should the line of sight be higher than a convenient level of the gunner's eye, the wheel 29 is operated to lower the sleeve until a sight may be effectively and conveniently taken. Should the line of sight be such as to require the gunner to hump his back and duck his head, or either, the wheel 29 is operated to elevate the sleeve to accommodate the line of sight to his eye while he assumes a normal posture.

The target being in sight, more definite azimuth and elevational aim is effected by moving the gun on the pin 33 as a pivot to attain proper elevation and by rotating the gun by hand on the vertical axis of the swivel 31, and including the swivel head, independently of the pedal drive.

In case the target is a moving one at a considerable distance the gunner makes no effort to obtain a fine azimuth sight by the use of the pedals, but only initially obtains a mean or near position of the gun in this respect, thereafter pointing the weapon by the independent movement which is not affected by pedal operation. As the target moves one way or another beyond an angle of five or ten degrees or some practical maximum, the pedals may be operated to move the gunner and

shaft 18 to or toward the proper azimuth plane. This movement may be effected during firing while the gun is independently held on the target by the grip 61 or other traverse means, or the pedals may be operated during intermission of firing.

In the case of a rapidly moving target, especially one moving on a tangent of a short radius from the gunner, the coordinated use of the pedal and hand traverse become specially important and valuable. Also the rapid change of elevation of the gun under such circumstances will make the use of the sight level accommodation means a most valuable adjunct since it avoids disturbance of the physical balance of the gunner, enables him to use his eye with a normal posture of the body and head, and obviates the distraction involved in stepping around over obstructions or ground inequalities and disturbances of balance such as may occur for instance when a tripod leg compels taking a posture without the gunner's feet being symmetrically adjusted to the center of gravity of his body.

Various servo motor devices or power means may be applied to the movements of the gun in elevation and traverse where practicable, and also to the raising and lowering of the gun translatably in place of the wheel 29 and rack 28. Thus in Figures 8 to 11 inclusive, I have shown a construction wherein the raising and lowering are accomplished hydraulically, so that a fluid supply under pressure may be maintained by well known means and the mount constructed as a hydraulic jack for raising and lowering the gun translatably.

Hydraulic lift.—Here the hydraulic foot piece 65, Fig. 19, corresponding to the one 15 and similar in form, has a pressure oil conduit fitting 66 connected by flexible or other conduit 67 to an oil pump not shown. From the fitting 66, an inlet port or duct 68 opens into the central bore 69 of the foot piece, while a short distance thereabove an outlet port or duct 70 opens radially from the bore to a return or vent conduit 71 which may be connected to the intake of the oil pump or a reservoir. A ball bearing 72 supports in the bore a revolute steel shaft or standard 73 circular in cross section from the bottom of which two rectilinear bores 74 and 75, parallel to the axis of the standard, extend to a level some distance above the throw of the pedals 22 of this machine. A ring gear 17, planetary gears 20, crank 21 and pedal 22 assembly are included, similar to that first described, the standard being retained against upward movement by a C-spring 76 engaged in a groove in the standard and confined by the ring gear as before. The bores both open laterally through the face of the standard and are counterbored and threaded to receive flexible conduit connection nipples 77 and 78 for purposes to be described.

The bore 75 is plugged at the lower end of the standard and a lateral vent port 79 formed therefrom through the side of the standard at the same level as the vent duct 70 of the foot piece. A horizontal circumscribing internal vent port groove 80 is formed in the wall of the bore 69 at the level of the duct 70 and port 79, so as to form uninterrupted communication between the standard bore 75 and the external return conduit 71.

Below the retainer spring 76 the standard is suitably grooved to receive a series of packing rings 81, and also, below the port groove 80 a second series of packing rings 82 are incorporated on the standard.

The standard is also bored from the top downward to provide a single large combined inlet and outlet bore or duct 83, stopping short of the upper terminations of the bores 74 and 75. A radial bore 84 is extended through the side of the standard from bore 83, forming a combined cylinder inlet and cylinder outlet 84 and including a nipple 85 for connecting flexible conduit thereto.

On the standard there is slidably fitted a cylinder 86 corresponding to the sleeve 26, but, contrary to the first described form no rack and pinion are incorporated, and no swivel piece is mounted for relative rotation on the cylinder. Instead, ears 87 corresponding to those 32' first described are fixedly provided on the upper end or head of the cylinder, and between these ears the rocker head or knob 32 may be pivoted as first described, or other mounting of the gun for elevational movements provided. The gun will still be swivelled for free movement, since the cylinder is rotatable freely around the standard. This free rotation may be unlimited or not, in this device, as discretion may dictate.

On the standard near its upper end a series of packing rings 88 are fitted in corresponding grooves 89 in the periphery of the standard, and slidable in the cylinder.

To effect raising of the gun translatively, or to lower it, or to hold it at various positions, in this translative movement on the mount, I have provided a conventional three way valve 90 mounted on the outside of the cylinder 86 above the inlet 84 in any convenient manner as shown in Figure 8, although various forms of valves suited to the functions required are available. In this instance the valve is shown as a simple plug type valve, including a case 91 of circular form having a conical seat 92 through which open radially a pressure inlet port 93, a larger vent or return port 94, and a combined inlet and outlet port 95. A plug valve 96 is fitted to the seat having a segmental closure part 97 of sufficient extent circumferentially to close only one of the ports at a time, and having means to stop its movement toward the pressure inlet port, so that the latter is never closed. The latter in this instance is illustrated at the upper side of the case in Figs. 8 to 10 and the other two ports diametrically opposite each other on a diameter normal to the radius of the port 93.

With the segmental part 97 at the position shown in Fig. 10 all three ports are open and oil or other liquid from port 93, as well as from liquid port 95 is free to the vent or return port 94.

The valve is suitably fixed on the outside of the cylinder 86 conveniently for operation by the gunner in the seat 25, and from the nipple 85 a flexible conduit 98 with a suitable slack loop is extended to and connected to the valve in communication with the port 95. From the nipples 77 and 78 similar connections 99 and 100 are made with the ports 93 and 94 of the valve.

Operation

The last described form of the invention may be mounted on a swinging crane or deck the same as first described and in the case of the crane adequate provision of slack in the leads (not shown) to conduits 67 and 71 should be made and conventional precaution against fouling may be included. Assuming that the gun is positioned and ready for operation with the gunner seated at the gun, the approximation of azimuth position is effected by the pedal operation as before, and the exact azimuth pointing accomplished in-

dependently by pivotal movement of the gun and cylinder 86 by hand. No means is indicated to limit the relative rotating movement of the cylinder and standard, since this will be automatically limited by the position of the gunner on the seat 25. Elevation of the gun for range is effected conventionally. Translational raising and lowering of the gun and cylinder are controlled during firing or intermission of firing and during change of elevation and azimuth pointing if necessary, by operating the handle 101 of the valve to the desired position. With the valve in the position shown in Fig. 9 the outlet port 94 is closed and the pressure liquid is admitted from the conduit 67 through the space under the lower end of the standard, small bore 74, nipple 77, flexible conduit 99 and port 93 to the valve case, from whence it passes outward through the two way port 95 and flexible conduit 98 to the bore 83, thus exerting its hydrostatic pressure in raising the piece, when the gun has reached a proper level, it may be held at a fixed elevation by turning the valve to the position shown in Fig. 10 the port 95 is closed, thus sealing in the cylinder whatever liquid may have gained access to the cylinder. For lowering the gun translatively the valve is returned to the position of Fig. 1 with the resulting venting of the liquid both from the cylinder and the pressure port, to the large outlet port 94, flexible conduit 100 and bore 75, groove 80, duct 70 and conduit 71, to the reservoir and/or pump not shown.

Cradle.—In Figs. 15 and 16 I have shown a cradle support for the gun at the top of the rotating base pivot head on the upper telescoping member or sleeve, and also a construction by which an extreme elevation may be given the muzzle of the gun without causing interference between the head of the gunner and mount, when the breech of the gun is close to the pivot on which the elevational movement occurs and to the vertical axis of rotation of the gun. In this instance, the construction of the gun may conform to the embodiment first described except that the uppermost member 102 of the mount rotatable on a vertical axis is formed with a horizontal offset or crank arm 103, the outer end of which is turned upwardly, and has the swivel 31' mounted thereon as in the case of the swivel 31 before described, in place of the ears 32' however, a sector plate 104, in the form of a narrow segment of a hollow cylinder with horizontal axis is fixed on the extremity of the offset with its ends directed upwardly but subtending less than 90 degrees, the chord disposed at an angle of 45 degrees or less to the horizontal and the lower part of the segment being toward the position of the gunner. This sector plate has parallel lateral edges and the abutting edge portions project at each side so as to afford continuous edge portions 105 engaged between upper and lower guide flanges 106 carried by side frame and guide plates 108, one at least being separable for ready removal of the gun. The plates are fixed on the framing or other suitable parts of the gun or breech mechanism. On one of these a grip and trigger 109 is mounted on a tongue 110 of suitable material extended diagonally and divergently from the axis of the gun, so that the hand of the gunner and the grip will not interfere with the head of the gunner in sighting the piece, as may be appreciated from the views in the drawings.

Operation (Figs. 15 and 16)

75 In the use of the last described form of the in-

vention, with the side plates 108, the pedal devices are employed as before, and independent pivotal movement of the gun and elevational pointing are effected as before described, as well as translational raising and lowering of the gun. Due to the use of the sector and guide frame the axis of pivotal movement of the gun is located nearer the gun axis and also the breech end of the gun is brought forward near the axes of pointing movement. This lessens the extent of translative vertical movement of the gun required to accommodate the position of the gunner to the line of sight, as may be understood from the illustrations of this form of the invention. In this construction the forward end of the sector plate may serve as a stop for movement of the gun muzzle downward.

It should be noted that while the gun is offset laterally from the vertical axis of the main standard portion of the mount laterally with respect to the direction in which the gunner normally faces, it is not necessary to similarly offset the gunner's seat or the pedal drive assembly, as the offset is so slight that the gunner can easily sight the gun without a strained position, and effect the operation of the gun and raising and lowering devices.

It will be understood that the offset 103 may be omitted and the sector plate 104 mounted on a simple end of the cylinder or the swivel of the first described construction.

It is thought unnecessary to illustrate the substitution of a binocular in place of the gun for searchlight control, or the mounting of listening devices in place of the gun, since the operation of the mechanical essentials of the invention will be much the same. In the case of a listening device using electronic relays, it is not always necessary to align the eye or ear of the operator with incident sound waves, but the mechanism described will enable rapid and accurate direction of the sound receivers, and a fine following of the course of a moving sound source, and the translational raising and lowering device may be disregarded to a large extent. However, where a number of planes are within sight or may be seen by optical instruments, it may be of advantage to use a binocular on the mount associated with a sound locator by Selsyn control and drive so that particular planes may be selected to determine identity or range where possible by distinctive sounds. These adaptations will be readily understood and the operative means for the controls being already available and in use are not illustrated herein.

In other instances a searchlight or sound lo-

cator may be mounted directly on the mount in place of the gun, for direction at or toward targets or other objects.

In place of the swinging crane any other form of extensible support may be employed, slidable or otherwise.

While illustrated as being in two halves bolted together at a diametrical joint, the foot pieces 15 and 65 are each preferably formed in one piece 10 if cast, and then suitably bored to afford the necessary bearings, this being a matter of discretion and not illustrated.

I claim:

1. In a mount of the character described, a 15 base, a primary person carrying mount element mounted for rotation on a vertical axis, and a final mount portion consisting of a cylindrical upwardly presented open end member rotatable with the primary mount element, and a head part 20 rested on said end and having a shank portion set revolvably in said end, a recess being formed in said end extending over a part of its circumference, a lug on the head movable in said recess to limit relative rotation of said head on the mount, 25 and a rocking support for an instrument on the head.
2. The structure of claim 1 including resilient 30 yielding motion limiting means between the lug and the ends of the recess in respective directions of relative movement of the lug.

MYRON C. SPENCER.
